UNITED STATES PATENT OFFICE.

WILLIAM L. WATERS, OF MILWAUKEE, WISCONSIN.

ELECTRIC DISTRIBUTING SYSTEM.

1,250,536.

Specification of Letters Patent. Patented Dec. 18, 1917.

Application filed May 25, 1914. Serial No. 840,670.

To all whom it may concern:

Be it known that I, WILLIAM L. WATERS, a citizen of the United States, residing at Milwaukee, in the county of Milwaukee and 5 State of Wisconsin, have invented certain new and useful Improvements in Electric Distributing Systems, of which the following is a full, clear, concise, and exact description, reference being had to the accompanying drawings, forming a part of this 10 specification.

The subject-matter of this invention is an electric distributing system.

The tendency in modern central station 15 practice is to supply a service to the consumer at a flat rate charge on a basis of maximum demand. This is due to the limited output of a given central station installation and an effort to secure economy and 20 efficiency by maintaining the central station apparatus working at its maximum output at all times and avoiding the undesirable characteristic of a peak load. This applies 25 to electric central stations, or to central stations supplying gas, water, steam, or any similar service.

In supplying current, it is desirable that the central station have an even and uniform load throughout the twenty-four hours 30 of the day and that at no time should the load on the central station exceed this maximum, nor, for reasons of economy, drop below it. Upon this basis, a central station may be operated in an economical manner 35 and current can be supplied to the consumer at a relatively low charge per unit of service. This ideal condition can be attained only when each consumer requires a uniform supply throughout the entire day. The consumer using a uniform current throughout 40 the entire twenty-four hours can secure a lower rate per unit of service, because of the possibilities of economical operation of the central station. This presents to the consumer the difficulty of maintaining a constant load, which will not exceed a given maximum and for obvious economical reasons should not drop below the same, as a flat rate charge based on a maximum de- 45 mand takes no account of a failure to use the service to which the consumer is entitled. A fairly constant load can be provided by employing various heating and cooking devices, and having a heat storage reservoir 50 which may be a heat storage stove or a hot

water heating system, or some device which can absorb the surplus current which is not otherwise used during periods of comparative idleness of the system, and turn it into a form of energy which is readily available 60 at any later period. The storage device or devices must be of sufficient capacity to consume practically all the current when the more important classes of circuits are not in use. 65

One of the objects of the present invention is to provide a system of load distribution which will allow the connection of only a predetermined load to the service main, but will allow the load to be changed automatically from one type or piece of apparatus to another. 70

A further object of my invention is to provide a system of load distribution which will always serve the more important load 75 in preference to the less important load and will, at the same time, maintain a constant load.

Another object of the invention is to provide an improved maximum demand meter 80 for automatically disconnecting a part of the load to maintain a condition of constant maximum load.

Another object of my invention is to provide a number of consumption outlets having mechanically interlocking means to insure the connection of only a predetermined load through said outlets. 85

A still further object of the invention is to provide an improved interlocking switch 90 structure.

According to my invention the total load is divided up into a number of separate service circuits of approximately equal capacity. Where a particular load is too great for a 95 single circuit it may be divided up into a number of circuits.

A bank of switches is provided for controlling these service circuits. These circuits may be of a total capacity far in excess of 100 the maximum demand for which the consumer is paying and it is necessary that at no time should more than a certain number of these circuits be connected, otherwise the maximum demand would be exceeded and 105 the excess current would necessarily be purchased at an unduly high rate, or a penalty or fine would be incurred.

The bank of switches is so constructed that only a certain predetermined number 110

of switches can be connected at a time, and if current be required in a circuit of greater importance when a circuit of less importance is already in circuit, the circuit of less importance is opened when the circuit of greater importance is connected. This is accomplished by an integrating mechanism which becomes active only when the sum or integral of the connected circuits exceeds the predetermined value and which invariably disconnects the circuit of least importance when the load is about to exceed the predetermined value.

In the drawings,

15 Figure 1 is a plan view of a bank of switches for making the connections of the various service circuits;

20 Fig. 2 is an elevation of one of the switch mechanisms showing the pivoted integrating weight in cross section;

25 Fig. 3 is the same as Fig. 2 except that the switch has been moved to the open position;

Fig. 4 is a diagram of the service circuits 25 and connections.

An illustrative number of service circuits have been indicated in Fig. 4 and the same are arranged in the relative order of their importance. The lighting circuit 1 containing incandescent lamps 10 is assumed as the circuit of first importance and is controlled by a switch 11. The circuit 2 of next importance may supply the elevator motor 20 with current. This circuit is controlled by the switch 12. The next circuit 3 is connected to a cooking or heating vessel 30 and is controlled by the switch 13. The circuit 4 supplies current to a different type of heating or cooking device 40, in this case 40 shown as a percolator. This circuit is controlled by the switch 14.

The circuit 5 of relatively least importance, supplies current to the heater 50 which may be a heat storage stove, a heater 45 for a hot water system, or the like. This circuit which is controlled by the switch 15, may be one of the "overflow" circuits.

Any desired number or class of circuits may be employed and the relative importance of the circuits may be determined in 50 any preferred manner. The circuits indicated above are shown merely for the purpose of illustration, to set forth one manner in which the invention may be practised.

55 These various circuits are connected to the mains 16 and 17 through the wires 18 and 19 and through the switch 21. Each of the service circuits may contain a fuse and the connection to the mains may contain a 60 fuse 22 and the coil of a load limiting or similar device 23.

Each of the switches is controlled by a corresponding lever 24 pivoted at 25 to swing the corresponding switch arm into 65 and out of connection with a fixed contact

26. Figs. 2 and 3 show the structure of an individual switch; in this case the switch 11 appearing at the extreme left in Fig. 1. The other switches are similar and need not be separately described. The contacts 26 70 are mounted on a stationary bar 27 in any suitable manner. The switch arm 11 is connected to the lever 24 through a slotted arm 28. A pin 29 mounted on the switch arm projects into the slot 31 of the arm 28. A 75 spring 32 is connected at one end to the switch arm by a pin 33 connected above the pivot point of the switch arm. The other end of the spring is connected below the pivot point of the switch arm to a pin 34 80 mounted on the base or support 35. It can be seen that the switch arm 11 is thus given a snap action, although this is not of the essence of my invention.

The lever 24 is hollow and the sliding 85 latch 36 is mounted in the bore thereof. A spring 37 normally holds the latch in extended position to allow engagement of the end of the latch with the pivoted integrating weight 38. The latch may be withdrawn by means of the latch lever 39 pivoted on the main lever 24 at the point 41. A link 42 connected at one end of the latch 36 by means of the pin 43 connects the lever 39 with said latch. A suitable handle 44 90 95 which may be of insulation is provided on the end of the lever 24. Each of the levers 24 is statically unbalanced and tends to move the switch to the open position as the outer end bearing the handle 44 is considerably heavier.

The integrating weight 38 is normally supported on the cross bar 48 but is pivoted on the rod 45 and is free to swing upward about said rod. The weight 38 is so proportioned that it will counterbalance a definite number of these levers but upon engagement of another lever the weight 38 will be overcome and will swing about its pivot 45 to release one of said levers (see 110 Fig. 3). To secure disconnection of the proper switch the arcs of engagement of the different switches are of different lengths, so that when the weight 38 swings upward the levers 24 will be freed in a predetermined order and they will, in consequence, release the corresponding switches in the same predetermined order. This effect may be secured by having a series of notches or 115 steps of various depth cut into the edge of the pivoted weight 38 as shown in Fig. 1, or it may be secured by making the latches 36 of the various levers of a graduated length so that upon an upward movement of the weight 38 about its pivot 45 the lever 120 having the shortest latch will be first disengaged. Upon a further motion the next longer lever will be disengaged and so on until the number of levers disconnected is sufficient to allow the weight 38 to pre- 125 130

ponderate and to retain the remaining levers and switches in their connected position. The slot 31 in the arm 28 of each of the levers, allows of sufficient free upward motion of the inner end of the lever 24, as to disengage the latch 36 from the weight 38 before the switch blade is disconnected. Hence the rocking of the levers does not disturb any of the switches.

0 Stop bars 46 and 47 may be provided for limiting the movement of the levers in the upward and downward directions respectively, and the bar 48 may be provided for supporting the weight 38 in its proper position. The circuit of greatest importance will be connected to the switch lever having the longest arc of engagement with the weighted bar 38 and the circuits of less importance will be connected with the levers of decreasing length of contact with the bar 38.

The operation of the system is as follows: Assuming that a maximum of three out of five circuits indicated may be connected, and it is evident at this point that any number of circuits may be employed and that the maximum number may be any part thereof, the desired number of circuits are closed by grasping the handle 44 and latch lever 39, and swinging the lever 24 upward to bring the switch blade into the closed position. The lever 39 is released and the weight 38 engaging the latch 36 retains the switch in closed position.

Assuming that circuits 1, 2 and 4 had thus been connected, (see Fig. 4), and it is desired that circuit 3 be put into service, the switch blade 13 will be swung into engagement with the fixed contact and the latch member 36 of that lever will engage the pivoted weight 38. The total number of levers is in excess of the predetermined maximum which was determined as three and as a consequence the weight of the bar 38 is insufficient to overcome the combined weight of the connected levers. The weight 38 will be swung upward (see the dotted lines in Fig. 3) and the switch lever having the shortest arc of engagement with the bar 38 will be freed from engagement with said bar. In the supposed case, this will be the lever controlling the switch arm 14. After disengagement of the switch lever controlling the fourth circuit, the weight 38 will be sufficient to overcome the combined weight of the other three levers and will retain the switch levers in closed position. The counterbalancing effect of the bar 38 may be increased by the addition of graduated weights or by suitable spring tension.

Instead of depending upon the weight of the outer end of the lever 24, I may employ a construction which I consider to be the equivalent, that is, I may construct these levers so that they are statically balanced and secure the biased action by means of

spring tension, or the like. This would prevent any jarring of the structure from tending to disengage the latch 36 from the weight 38. I may also employ spring tension to secure the effect of the weighted bar 38.

If it is inexpedient to make all of the service circuits of approximately the same capacity, the weighted lever 24 controlling such a circuit, may be made of a different weight so that the ratio of the weight of this lever to the other levers will be approximately the same as the ratio of the capacities of the circuits. A number of such circuits, the consumption capacity of which would be equal to one of the larger circuits, might have levers engaging approximately equal arcs of contact with the weighted bar 38 so that the addition of one of the larger capacity circuits would disconnect this number of smaller circuits upon the larger capacity circuit being connected.

When it is desired to disconnect any one of these circuits the lever 39 may be grasped with the handle 44 whereby the latch 36 is withdrawn from contact with the weight 38 and the switch lever may be moved to the down or open position as shown in Fig. 3. Or the switches may be disconnected if desired, by pulling down on the handle 44 of the appropriate lever. This action would, of course, disconnect the switch arm so actuated and the switch arms of the connected circuits of lesser importance, hence, all of the switches may be disconnected by pulling down the handle 44 of the connected switch of greatest importance.

From the above it can be seen that I have provided a switching mechanism which will retain in circuit the predetermined maximum of service circuits and which will disconnect, when it becomes necessary to do so, a circuit of lesser importance to allow of the connection of a circuit of greater importance. The weight 38 is, in effect, an integrating means for summing up the number of connected circuits and for disconnecting any excess above the predetermined maximum. The disconnection as above stated, will be made in each case inversely in the order of importance of the circuits.

The above described system of distribution is applicable, not only to electric supply systems, but is equally well adapted to control similar systems supplying steam, 120 water, gas or any similar service.

Although the invention has been described with reference to the detail of construction of a specific embodiment, it is not intended thereby, in any manner, to limit the invention as I consider the above described system of distribution to be broadly new and desire that the claims be construed as broadly as possible.

Numerous modifications will immediately

be apparent to those skilled in the art, all of which come within the spirit and scope of this invention.

What I claim as new and desire to secure by Letters Patent of the United States is:

- 5 1. In a system of electrical load distribution a plurality of service circuits of relatively graded importance, a plurality of switches for connecting said service circuits to the supply mains, a plurality of levers each connected to a switch and biased to move its corresponding switch to the open position, a movable detent adapted to overcome the bias of a predetermined number 10 of said levers to hold the corresponding switches in a closed position, said detent, releasing the levers inversely in the order of their importance when greater than a predetermined number of switches are connected.
- 15 2. In combination a plurality of service outlets, a plurality of biased levers controlling the connections of said outlets to supply mains, and a weight adapted to overcome the bias of a predetermined number 20 of said levers to hold them in the closed position, all of said levers having different lengths of arc of engagement with said weight.
- 25 3. In a load distributing system, a main supply circuit, a plurality of feeder circuits, a plurality of switches, one for each of said feeder circuits to connect said feeder circuits to said supply circuit to simultaneously feed a fraction of the total number of circuits, common, mechanical interlocking means for retaining a plurality of said switches in closed position, and means connected with each switch adapted to 30 operate with said interlocking means, said interlocking means allowing the substitution of one connection for another but preventing the connection of more than a predetermined number of circuits to said mains.
- 35 4. In a load distributing system, supply mains, a plurality of feeder circuits, switches for connecting said feeder circuits to said supply mains, a common mechanical interlocking means exerting a force for retaining said switches in closed condition, means associated with each switch exerting a force tending to release the retained switches from the interlocking means, said last force being proportional to the maximum capacity 40 of a fraction of the circuits when simultaneously connected.
- 45 5. In a load distributing system, a common supply circuit, a plurality of feeder circuits, switches for connecting said feeder circuits to said supply circuit, a common mechanical retaining means exerting a predetermined action in proportion to the total maximum load to be drawn from said supply mains by the connected feeder circuits,
- 50 and means associated with each switch exerting a force to release the associated switch from the retaining means, said force being relatively proportional to the maximum capacity of the associated circuit.
- 55 6. In a system of load distribution, a common supply circuit, a plurality of feeder circuits, switches for connecting said feeder circuits to said supply mains, a common mechanical retaining means for retaining said switches in closed condition, and means associated with each switch exerting a force to release the associated switch from the retaining means, said force being proportional to the capacity of associated circuit, said retaining means, when the force thereof is overcome by the combined force of a number of said associated means, releasing the connected switches in a relatively predetermined order.
- 60 7. In combination, a supply circuit, a plurality of feeder circuits, a plurality of switches, each switch associated with a feeder circuit, a mechanical current limiting device coöperating with said switches to retain them in closed position, each of said switches having retracting means tending to retract the associated switch from control of said current limiting device, the tendency of said retracting means being relatively proportional to the maximum capacity of the associated circuit, said current limiting device being capable of retaining only a predetermined number of said switches in closed position, whereby only a predetermined load can be drawn from the supply mains.
- 65 8. The method of distributing a predetermined maximum load among a plurality of possible connections of greater total capacity than said maximum load which consists in establishing a predetermined order of importance among all of the possible connections or combination of connections, independently integrating any combination of the connections until they total the predetermined maximum, and automatically disintegrating the connections inversely in the order of their importance simultaneously with the independent addition of further load.
- 70 9. In a system of load distribution, a plurality of service outlets of various relative importance, a plurality of circuit closers to independently and indifferently control said outlets, and means to retain any group of said circuit closers when moved into closed position up to a predetermined maximum and to release a group of the same corresponding to the group connected in excess of such predetermined maximum.
- 75 10. The combination of a main supply circuit, and a plurality of work circuits, a plurality of levers to control the work circuits to supply current to a group thereof.

simultaneously up to a predetermined maximum, and a counterbalance exerting a force on said levers equal to the combined weight of a group of the levers below said predetermined maximum proportional to a fraction of the work circuits to maintain the total current consumption thereof constant.

In witness whereof, I hereunto subscribe my name this 20th day of May, A. D. 1914.

WILLIAM L. WATERS.
